FIG. 1

FIG. 4

FIG. 2

FIG. 3

FIG. 9

FIG. 5

FIG. 6

FIG. 7

FIG. 8

FIG. 1 is a top plan view of a pull tab for a tear strip opener showing our new design:

FIG. 2 is a bottom plan view thereof;

FIG. 3 is an enlarged sectional view taken across the ribbed portion thereof;

FIG. 4 is a back elevational view thereof;

FIG. 5 is a top plan view of a pull tab for a tear strip opener showing another form of our design wherein the spaced longitudinally oriented ridges are of a modified shorter form from that form shown in FIG. 1;

FIG. 6 is a top perspective view of a pull tab for a tear strip opener of another form of our new design wherein the forward end thereof is of a modified form from that shown in FIGS. 1 through 5;

FIG. 7 is a top perspective view of a pull tab for a tear strip opener showing another form of our new design similar to the form of FIG. 6, but wherein the spaced longitudinally oriented ridges are of the shorter form shown in the FIG. 5 drawing;

FIG. 8 is an enlarged sectional view taken across the ribbed portion of the form of the invention shown in FIGS. 6 and 7; and

FIG. 9 is a back elevational view thereof.

The characteristic feature of the design is the appearance of that portion of the design below the gripping ring as shown in FIGS. 1, 5, 6 and 7.

We claim:

The ornamental design for a pull tab for a tear strip opener, substantially as shown and described.
